UNITED STATES PATENT OFFICE.

JOHN HERBERT EVERINGHAM, OF MANCHESTER, ENGLAND.

PORTABLE CARRIAGE FOR CHILDREN.

1,327,864.

Specification of Letters Patent. Patented Jan. 13, 1920.

Application filed August 28, 1919. Serial No. 320,443.

To all whom it may concern:

Be it known that I, JOHN HERBERT EVERINGHAM, a subject of the King of Great Britain and Ireland, and resident of Longsight, Manchester, England, have invented certain new and useful Improvements in or Relating to Portable Carriages for Children, of which the following is a specification.

10 This invention relates to portable carriages for children and has for its object to provide a child's carriage which, while being comfortable in use, is yet of such a small size that when the handle is removed it can 15 be readily picked up and carried or stored on tramcars or in railway carriages without any collapsing of the same, and which is also applicable for use as a toy.

The invention will be more particularly 20 described by the aid of the accompanying drawings wherein:

Figure 1 is a side elevation of a child's carriage constructed according to the invention.

25 Fig. 2 is a plan view, and
Fig. 3 is a rear view of Fig. 1, while
Fig. 4 is a perspective view.

Figs. 5 and 6 show the bracket and drawing handle in detail.

30 Fig. 7 shows a modified rear support for the carriage.

In carrying the invention into effect according to the drawings the wheel axle *a* is secured to the underside of the base board 35 *b* which is approximately 9 inches deep by 12 inches wide and to the top front edge of which is secured a vertical board *c* of the same width and about 3 inches in height. To the top edge of the vertical board *c* is 40 hinged at *d* the front edge of the seat *e* which is of approximately the same dimensions as the base and to which are secured a suitably shaped back *f* and sides *g*. The rear of the seat is supported upon a spring or springs 45 *h*, *h* either of the leaf variety or preferably of the spiral kind as shown. Usually two of such springs are used along the back edge of the seat and connected to said seat and the base respectively.

50 Two forwardly and downwardly extending legs *i* of hoop iron are provided at the front corners of the base and said hoop iron may extend along the edge of said base and shaped or recessed to constitute clamps *j* 55 to secure the axle in position. The free ends of the legs are rolled over to grip a cross bar

k at the outer extremities of which are provided rubber rollers *l*, *l* to prevent unduly jarring the occupant of the carriage in the event of striking an obstruction. 60

A similar rearwardly and downwardly extending leg *m* is provided to prevent the carriage tipping too far backward and such leg is conveniently formed of tubular metal with the free end split or forked to receive a 65 rubber anti-friction roller *n*.

In the middle of the vertical board a bracket *o* is secured carrying a disk *p* the face of which is serrated to receive the correspondingly serrated disk *q* on the end of a 70 shaft *r* provided with a suitable holding handle *s* at its free end. The two disks are kept in engagement by a nut and bolt *t* which can be slackened back when it is required to remove the shaft or to vary the 75 inclination of the same.

When used as a carriage the handle is adjusted to the right height for the person drawing the same and the child placed on the seat with its feet resting on the cross rail 80 *k* which just clears the ground when the carriage is drawn or pushed along the same.

When it is desired to take the carriage on a tramcar or train the shaft *r* is removed and the carriage is lifted by the back, in 85 which a handle *u* is formed for the purpose. It can be readily carried or stored as it merely constitutes a small regularly shaped article the overall dimensions, even when a 90 comfortably shaped back and sides are used being approximately 12 inches in depth, 14 inches in width and 16 inches in height.

In some cases, particularly when it is desired to use the carriage over rough ground it may be desirable to form the rear depending leg *m* hinged so that it can be turned out of the way. Fig. 7 shows the leg *m* so adapted the inclined portions *m*¹, and *m*² being acted upon by the spring *v* in order to retain the leg in the open or closed position, as 100 illustrated by full and dotted lines respectively.

It will thus be seen that no collapsible parts are required to adapt it for transit thereby avoiding trouble and allowing the 105 axle to be rigidly fixed in position consequently the wheels can be set true and remain so in use over the roughest roads. Further, the construction and size is such that by a suitable adjustment of handle it 110 may be propelled by the child itself and used in the nature of a toy.

What I claim is:—

1. In a go-cart for children, an axle having relatively small wheels thereon, a base or frame secured to said axle, an upright member rigidly secured to the front edge of the base or frame, a small seat, with back and arms, hinge-wise connected along one edge to the top of the upright member, springs positioned between the other edge 10 of the seat and the base to receive the weight in compression, a depending cross rail secured to the underside of the base at the front to form a foot-rest and prevent forward tilting, a pendant leg secured to the underside of the base at the rear to prevent 15 rearward tilting, and a holding handle pivotally connected to the upright member at the center, substantially as herein set forth.
2. In a go-cart for children, an axle having relatively small wheels thereon, a base or frame secured to said axle, an upright member rigidly secured to the front edge of the base or frame, a small seat, with back and arms, hinge-wise connected along one 20 edge to the top of the upright member, springs positioned between the other edge of the seat and the base to receive the weight in compression, a depending cross rail secured to the underside of the base at the front to form a foot-rest and prevent forward tilting, a depending leg pivotally secured to the underside of the base at the rear and adapted 25 to be turned to the operative or inoperative position, anti-friction rollers on the front and rear pendant members, and a holding handle pivotally and removably connected to the upright member at the center, together with a handle to lift the carriage bodily, substantially as described.

cured to the underside of the base at the rear and adapted to be turned to the operative or inoperative position, anti-friction rollers on the front and rear pendant members, and a 35 holding handle pivotally and removably connected to the upright member at the center, substantially as described.

3. In a go-cart for children, an axle having relatively small wheels thereon, a base or frame secured to said axle, an upright member rigidly secured to the front edge of the base or frame, a small seat with back and arms hinge-wise connected along one edge to the top of the upright member, springs positioned between the other edge of the seat and the base to receive the weight in compression, a depending cross rail secured to the underside of the base at the front to form a foot-rest and prevent forward tilting, a depending leg pivotally secured to the underside of the base at the rear and adapted 40 to be turned to the operative or inoperative position, anti-friction rollers on the front and rear pendant members, and a holding handle pivotally and removably connected to the upright member at the center, together with a handle to lift the carriage 45 bodily, substantially as described.

In witness whereof I have hereunto set my hand.

JOHN HERBERT EVERINGHAM.
